UNITED STATES PATENT OFFICE.

ALBERT H. DE VOE, OF WESTFIELD, NEW JERSEY, ASSIGNOR TO THE SINGER MANUFACTURING COMPANY, A CORPORATION OF NEW JERSEY.

STRIP FOLDING AND GUIDING ATTACHMENT FOR SEWING-MACHINES.

1,024,316.

Specification of Letters Patent.

Patented Apr. 23, 1912.

Application filed July 29, 1911. Serial No. 641,253.

To all whom it may concern:

Be it known that I, ALBERT H. DE VOE, a citizen of the United States, residing at Westfield, in the county of Union and State 5 of New Jersey, have invented certain new and useful Improvements in Strip Folding and Guiding Attachments for Sewing-Machines, of which the following is a specification, reference being had therein to the 10 accompanying drawings.

This invention relates to improvements in strip-folding and guiding attachments for sewing machines, and has to do primarily with the folding and attaching of 15 facings or button and buttonhole strips to men's and women's garments, especially those made from knit fabrics.

In the manufacture of garments from knit fabrics, it has been the common practice to employ a single facing as the button-hole strip.

This invention embodies means for securing upper and lower buttonhole strips arranged on opposite sides of said body fabric with their free longitudinal edges in alignment with and distant from the edge of said body fabric substantially one-half their width, which permits the under or button strip to be placed full width on the 30 body fabric, thus effecting a more desirable finish.

In the accompanying drawings illustrating the invention, in the several figures of which like parts are similarly designated, 35 Figure 1 is a view in perspective, in front end elevation, of the front end portions of a sewing machine bed-plate and bracket-arm equipped with the present invention. Fig. 2 is a plan view of the strip-folding 40 guide-plate. Fig. 3 is a plan view of the lower strip-folding guide. Fig. 4 is an underside view of Fig. 3. Fig. 5 is a plan view of the lower strip-folding guide shown in Figs. 3 and 4, with certain elements omitted to more clearly show the construction 45 of the main or body portion of said guide. Fig. 6 is a view, in perspective, of the lower fold-positioning blade and its carrying frame. Fig. 7 is a view, in perspective, of the 50 cloth-presser mechanism. Fig. 8 represents details, in perspective, of the mechanism shown in Fig. 7. Fig. 9 is a plan view of the integrally formed feed-dogs. Fig. 10 is a plan view of the lower strip-

folding guide-carrying plate. Fig. 11 illustrates one form of product effected by the present invention.

As the stitch-forming mechanism and the mechanism for actuating the integrally formed feed-dogs may be of any suitable 60 construction, the latter mechanism has been omitted and only so much of the former shown as is essential to an understanding of the operation of the invention.

Referring to the figures, 1 represents the 65 front end portion of the bed-plate of a sewing machine, 2 the like portion of the bracket-arm, 3 the head of said arm, 4 the needle-bar mounted in said head and provided at its lower end with the complementary eye-pointed needles, as 5, and 6, 7, 8, 9 and 10 the integrally formed feed-dogs.

11 represents the commonly employed spring-depressed presser-carrying bar mounted in the head 3 and carrying at its 75 lower end the cloth-presser bracket 12 provided with guideways, as 13, into which are mounted to move vertically the respective cloth-presser carriers 14 and 15 provided with the respective notches 16 and 17 80 into which the respective ends 18 and 19 of the equalizing rock-lever 20 extend, said rock-lever being pivoted upon the screw 21 threaded into said bracket.

To the horizontally arranged arms 22 and 85 23 of the respective carriers 14 and 15 are pivotally attached by pins, as 24, the respective rocking cloth-pressers 25 and 26 provided with the usual needle openings, as 27, each of said cloth-pressers having its front 90 end upturned, as at 28 and 29; and into each of the carriers 14 and 15 is threaded a screw, as 30, adjustable with respect to the upper surface, as 31, of the respective cloth-pressers to control the extent of rocking 95 movement of the latter, said screws being held against accidental adjustment by check-nuts, as 32, a cap-plate 33 secured by screws, as 34, threaded into the bracket 12 acting to hold the elements 14, 15 and 20 100 against displacement.

35 represents the throat or needle-plate secured by screws, as 36, to the bed-plate 1, and 37 the lower strip-folding guide-plate secured in like manner to said bed-plate. 105

The lower strip-folding guide for folding the longitudinal edges of the facing strip comprises the folding scroll plate 38

at the opposite edges of which are formed the folding scrolls 39 and 40, and between the flanged portions of said folding scrolls is secured, in the present instance by soldering, 5 a tongue-plate 41 having an extended tongue portion 42 which coacts with said folding scroll to form the folds at the opposite edges of the facing strip.

43 represents a bracket secured, as by 10 soldering, to the underside of the plate 38 and provided with lugs 44 and 45 having suitable openings in which a rod 46 is loosely mounted, and in said rod are secured by screws, as 47, the opposite ends of 15 a wire frame 48, said rod being torsionally held by a spring 49 in the direction indicated by the arrow *t*.

To the side of the folding scroll 40 is secured, as by soldering, an attaching plate 20 50 provided with openings, as 51, through which extend screws, as 51', threaded into openings, as 52, formed in the lower strip-folding guide-carrying plate 53, which latter is mounted in the guideway 54 formed 25 in the bed-plate 1, the movement of the plate 53 in the direction of the feed of the fabric being limited by the shoulder 55 contacting with the wall 56 of the lug 57 forming a part of said lower strip-folding 30 guide-plate and in the opposite direction by the shoulder 58 contacting with the wall 59 of said lug.

60 represents the lower fold-positioning blade secured by screws, as 61, to the upper 35 side of the tongue-plate 41 and provided at its forward end with extended portions, as 62, and 63 represents a body fabric guide secured by screws, as 64, to the plate 41.

65 represents a scroll guide bracket pivotally mounted on the stud-screw 66 threaded 40 into the bracket 67 which, in turn, is secured by screws, as 68, to the cloth-presser carrying bar 11, a spring metal plate 69 secured by screws, as 70, to said bracket acting 45 against the inner side of the head of said stud-screw to frictionally hold said bracket in its elevated position, the lug 71 determining the limit of its downward movement, and 72 represents the upper strip-folding 50 guide suitably secured to the outer end of the bracket 65.

73 represents the upper fold-positioning blade oscillating frame having formed integral with it a short shaft 74 mounted in the 55 bearing 75 formed in the bracket 76 extending out from the cap-plate 33, said shaft being provided with a collar 77, secured by screw 78, for holding it against movement in the direction of its length.

60 79 is the upper fold-positioning blade carrying rod mounted to slide in a suitable bearing formed in said oscillating frame and carrying at its forward end the upper fold-positioning blade 80, said blade carrying 65 rod being held against axial movement

by the guide-rod 81, attached collar 82 and groove 83, the movement of said blade in the direction of its operative position being limited by the collar 82 and in the opposite direction by the collar 84, secured by 70 screw 85.

86 represents a spring, suitably secured to the underside of the bracket 76, the outer end of which coacts with a flattened surface (not shown) formed on the shaft 74 to hold said blade in its elevated position, 75 as shown in Fig. 1.

The operation of the improved mechanism for effecting the product illustrated is as follows:—The cloth-presser is first raised in the usual manner to its elevated position, and the lower strip-folding guide, attached fold-positioning blade and wire frame are moved back from the line of needle actuation until arrested by the shoulder 58 contacting with the wall 59, followed by passing one end of the facing strip into the opening 88 and out through the delivery end 89 of said lower strip-folding guide (Figs. 3 and 4) thus forming the folds 90 and 91. When inserting the facing strip as above pointed out, the end thereof is carried beyond the free end of the fold-positioning blade 60 sufficiently to lay the fold 92, which is formed by folding the end of the facing strip back over the free ends of said lower strip-folding guide and fold-positioning blade, where it is held beneath the loop 93 of the spring-controlled wire frame 48. The body fabric 93' is then placed beneath 100 the presser-foot with the edge 94 in guiding relationship with the right hand wall 95 of the body fabric guide 63, when said lower strip-folding guide and attached elements, 105 together with the facing strip, are advanced into operative relationship with the stitch-forming mechanism with the fold 92 in position to be pierced by the needles, which is effected by the extended portions 62 of the lower fold-positioning blade passing in 110 between the feed-dogs and needles. To position the upper facing strip 96 in stitching position with respect to the body fabric, one end of said strip is passed into the opening 97 of the upper strip-folding guide 72 and 115 out through its delivery end 98, which forms the side folds 99 and 100, said strip being advanced sufficiently to form the fold 101, which is effected by the end of the facing strip coming in contact with the wire 102 120 carried by the cloth-presser bracket 12, followed by the upper strip-folding guide being adjusted downward to its limit of movement, when the upper fold-positioning blade 80 is moved in between the fold 101 and said facing strip and advanced to the limit of its inward movement, thus positioning said fold in stitching relationship with the previously positioned facing strip and the body fabric, after which the cloth-presser is low- 125

130

ered, the needles caused to pierce the fabric and the upper fold-positioning blade returned to its inoperative position, as shown in Fig. 1, the notches 103 and 104 formed in 5 the blade 80 permitting the free edge of said blade to position the fold 101 in line with the descending needles.

105 and 106 represent oppositely arranged fold-guides adjustably secured upon a plate 10 107 formed integral with the rocking cloth-presser 25 and acting to guide the longitudinal folds 99 and 100.

After the fabric and facing strips have 15 been positioned as above pointed out, the stitching operation is commenced and continued to within a short distance of the finished end, when both the lower and upper strip-folding guides are returned to their inoperative positions, the lower facing strip 20 severed in line with the groove 107 formed in the lower strip-folding guide-plate, and the upper facing strip severed to correspond in length to said lower facing strip, when the folds 108 and 109 are manually formed 25 and the stitching continued to the edge 110 of the body fabric.

Having thus set forth the nature of the invention, what I claim herein is:—

1. A fabric guide for sewing machines, 30 a lower strip-folding guide adjustably mounted on the bed-plate of the sewing machine and provided with means for folding the oppositely arranged longitudinal edges of a lower facing strip, a fold-retaining element, a fold-positioning element and a body fabric edge-guide carried by said lower strip-folding guide, in combination with an 35 adjustably mounted upper strip-folding guide provided with means for folding the oppositely arranged longitudinal edges of an upper facing strip and coacting with means for forming a fold across the end of said upper facing strip, and means for positioning said 40 last mentioned fold in operative relationship with the stitch-forming mechanism.

2. In a fabric guide for sewing machines, 45 a lower strip-folding guide secured to a carrying plate adjustably mounted on the bed-plate of the sewing machine, said lower strip-folding guide being provided with means for folding the oppositely arranged longitudinal edges of a lower facing strip, a fold-retaining element, a fold-positioning element and a body fabric edge guide carried by said lower strip-folding guide, in combination with an 50 adjustably mounted upper strip-folding guide carried by the cloth-presser carrying bar and provided with means for folding the oppositely arranged longitudinal edges of an upper facing strip and coacting with means for forming a fold across the end of said upper facing strip, and means for positioning said 55 last mentioned fold in stitching relationship 60

with the previously positioned facing strip and body fabric.

3. In a fabric guide for sewing machines, 65 a cloth-presser mechanism, a lower strip-folding guide adjustably mounted on the bed-plate of the sewing machine and provided with means for folding the oppositely arranged longitudinal edges of a lower facing strip, a fold-retaining element, a fold-positioning element, and a body fabric edge-guide carried by said lower strip-folding guide, in combination with an 70 adjustably mounted upper strip-folding guide provided with means for folding the oppositely arranged longitudinal edges of an upper facing strip and coacting with means carried by said cloth-presser mechanism for forming a fold across the end of said upper facing strip, and means for positioning said 75 last mentioned fold in operative relationship with the stitch-forming mechanism.

4. In a fabric guide for sewing machines, 80 a cloth-presser mechanism including compensating cloth-pressers, a lower strip-folding guide adjustably mounted on the bed-plate of the sewing machine and provided with means for folding the oppositely arranged longitudinal edges of a lower facing strip, a fold-retaining element, a fold-positioning element and a body fabric edge-guide carried by said lower strip-folding guide, in combination with an 85 adjustably mounted upper strip-folding guide provided with means for folding the oppositely arranged longitudinal edges of an upper facing strip and coacting with means carried by said cloth-presser mechanism for forming a fold across the end of said upper facing strip, and means for positioning said 90 last mentioned fold in operative relationship with the stitch-forming mechanism.

5. In a fabric guide for sewing machines, 95 a cloth-presser mechanism including compensating cloth-pressers, one of which is provided with oppositely arranged adjustably secured edge-guides, a lower strip-folding guide adjustably mounted on the bed-plate of the sewing machine and provided with means for folding the oppositely arranged longitudinal edges of a lower facing strip, a fold-retaining element, a fold-positioning element and a body fabric edge-guide carried by said lower strip-folding guide, in combination with an 100 adjustably mounted upper strip-folding guide provided with means for folding the oppositely arranged longitudinal edges of an upper facing strip and coacting with means for forming a fold across the end of said upper facing strip, and means for positioning said 105 last mentioned fold in operative relationship with the stitch-forming mechanism.

6. In a fabric guide for sewing machines, 110 a lower strip-folding guide mounted adjustable with respect to the bed-plate of the sewing machine and provided with a fold 115

retaining element, a fold-positioning element and a body fabric edge-guide, in combination with an adjustably mounted upper strip-folding guide provided with means for folding the oppositely arranged longitudinal edges of an upper facing strip and coacting with means for forming a fold across the end of said upper facing strip, and means for positioning said last mentioned

fold in operative relationship with the 10
stitch-forming mechanism.

In testimony whereof, I have signed my
name to this specification, in the presence of
two subscribing witnesses.

ALBERT H. DE VOE.
